E. ALBERTI,

SCREENING ATTACHMENT FOR CORK DISK CUTTING MACHINES.

APPLICATION FILED APR. 20, 1917.

1,257,171.

Patented Feb. 19, 1918.

UNITED STATES PATENT OFFICE.

EMILIO ALBERTI, OF NEW YORK, N. Y., ASSIGNOR TO INTERNATIONAL CORK COMPANY,
OF BROOKLYN, NEW YORK, A CORPORATION OF NEW YORK.

SCREENING ATTACHMENT FOR CORK-DISK-CUTTING MACHINES.

1,257,171.

Specification of Letters Patent. Patented Feb. 19, 1918.

Application filed April 20, 1917. Serial No. 163,404.

To all whom it may concern:

Be it known that I, EMILIO ALBERTI, a citizen of the United States, and a resident of the city of New York, in the county of 5 Kings and State of New York, have invented certain new and useful Improvements in Screening Attachments for Cork-Disk-Cutting Machines, of which the following is a specification.

- 10 The present invention relates to an attachment for disk cutting machines, and more particularly to means which screens out or separates the broken disks or chips from the perfect ones. The invention pertains to a 15 machine for producing disks from cork strips, which are to be employed in the manufacture of the well-known crown corks, or generally in the production of closures of the cap variety.
- 20 One of the objects of the present invention is to provide an attachment of the character described, which is simple in construction, efficient in operation, and that is actuated by one of the moving elements of the machine 25 without the aid of a special gearing.

With these and other objects in view, which will more fully appear as the nature of the invention is better understood, the same consists in the combination, arrangement, and construction of parts hereinafter described, pointed out in the appended claims and illustrated in the accompanying drawings, it being understood that many changes may be made in the size and proportion 30 of the several parts and details of construction within the scope of the appended claims without departing from the spirit or claims without departing from the spirit or sacrificing any of the advantages of the invention.

- 40 One of the many possible embodiments of the invention is illustrated in the accompanying drawings, in which:—

Figure 1 is a front elevation of a portion of a cork disk cutting machine with the attachment constructed in accordance with the present invention mounted thereon; and Fig. 2 is a section taken on line 2—2 of Fig. 1.

Herein only as much of the cork disk cutting machine will be described as is necessary to understand the operation of the screening attachment, the machine being more fully described in an application for U. S. Letters Patent filed by me on the 20th 50 day of Feb. 1917, under Serial No. 149,798.

Referring now to the drawings, the numeral 10 designates the supporting frame of the machine, upon the table portion of which rests a base 11, from which rises a set of bearings 12, in which is rotatably and reciproca- 60 bly mounted a tubular arbor 13. To this arbor is secured, for instance, by a clamping nut 14 a tubular cutter 15. The arbor is provided with a longitudinal groove 16 in its outer face, into which groove fits a feather 65 key 17, attaching to the arbor a pinion 18. The pinion is held against longitudinal movement between the bearings 12, the groove and key arrangement permitting of 70 lengthwise or reciprocating movement of the arbor, and also of rotary motion thereof. The pinion is driven from any suitable source of power by the intermediary of a driving chain (not shown). Into the arbor reaches a tubular discharge chute 19. This 75 chute is straight and is journaled in a bearing 20, registering with the bearing set 12. Near the outer end of the chute is mounted a stop ring 21, that is adapted to abut against the bearing adjacent the same. The 80 chute is connected with the arbor by a ring 22 and a screw 23, the connection being such that the chute reciprocates with the arbor, but does not rotate therewith. A ball bearing 24 is mounted upon the chute and abuts 85 against the outer end of the arbor and a shoulder 25 upon the chute. This ball bearing takes up the lengthwise thrust of the arbor. The bore 26 in the cutter is conical, the diameter of the bore at its cutting edge cor- 90 responding to the diameter of the disks to be cut, and the diameter at its inner end being somewhat larger for a purpose to be described. In a similar manner is the bore 27 of the chute tapered, it being smaller at 95 its inner end, that is adjacent the cutter, than at its outer end, at which the stop ring 21 is mounted.

The arbor and cutter are reciprocated, that is to say they are advanced toward and 100 retracted from the work. For this purpose there is keyed to a counter-shaft 28 an eccentric 29, to the strap 30 of which is attached in any suitable manner an eccentric rod 31, to which is pivoted at 32 a lever 33, 105 the latter being fulcrumed at 34 to the frame 10. The upper end of this lever is fork-shaped, as shown at 35, and in engagement with pins 36, that are carried by a sleeve 37 the latter being fixedly attached to 110

the chute 19. The counter-shaft is rotatably mounted in bearings 28' on the frame 10, and is driven from a driving shaft 38 by a suitable gearing, for instance a bevel gear 5 upon the driving shaft, in mesh with a bevel gear 39 upon the counter-shaft.

The cutter co-operates with a work support 41, the construction of which need not be given herein in detail, as it does not form 10 part of the invention.

The screening or separating attachment comprises a foraminated sheet or plate 42, that is provided with vertically extending side flanges 43, and with a flange 44 at the 15 end adjacent the chute 19. The foramina in the sheet or plate are each of a diameter that is smaller than the diameter of a disk to be cut on the machine. The sheet or plate is slightly inclined longitudinally toward its free end, as clearly appears from Fig. 1 of the drawings. The attachment 20 may be secured in any suitable manner to the chute, so that the disks discharged from said chute fall onto the said sheet or plate. 25 In the case illustrated in the drawings, the attachment is cast integral with the stop ring 21.

The operation of this device is as follows: 30 The cutter, in completing its forward stroke, that is to say its stroke toward the work holder, cuts a disk from the cork strip thereon, said disk remaining within the cutter, to be removed therefrom by those subsequently being cut. The finished product 35 moves through the discharge chute and falls onto the foraminated sheet or plate 42, which, by reason of its being attached to the chute,

is continuously reciprocated or vibrated, and thus separates broken pieces or chips from the disks. The disks pass toward the discharge end of the attachment, and thence into a receptacle not shown. The broken pieces or chips drop through the foramina in the plate 42 into a chute, not shown in the drawings. 45

From the foregoing it appears that the cutting mechanism includes an arbor, that is made of two sections, one of which is rotated and reciprocated, while the other one, hereinbefore termed "chute", has a reciprocating motion only. 50

The cutter and chute 19 are tapered toward their outer ends, to prevent a clogging of the same. The chute 19 reciprocates, but does not rotate with the cutter, as 55 otherwise a proper discharge of the finished product could not take place.

What I claim is:

1. The combination in a cork disk cutting machine of a tubular reciprocating arbor, 60 a tubular cutter attached to one end of said arbor, and screening means carried by the other end of said arbor adapted to receive the product issuing from said arbor.

2. The combination in a cork disk cutting machine of a tubular reciprocating arbor, 65 a tubular cutter attached to one end of said arbor, and a foraminated plate carried by the other end of said arbor adapted to receive the product issuing from said arbor. 70

Signed at New York, in the county of Kings, and State of New York, this 7th day of April A. D. 1917.

EMILIO ALBERTI.
